(57) **CLAIM**

The ornamental design for a vacuum cleaner body, as shown and described.

DESCRIPTION

1. Vacuum cleaner body

1.1 is a perspective view of a vacuum cleaner body, showing our new design;

1.2 is a front elevation view thereof;

1.3 is a rear elevation view thereof;

1.4 is a left-side elevation view thereof;

1.5 is a right-side elevation view thereof;

1.6 is a top plan view thereof; and

1.7 is a bottom plan view thereof.

The broken line shown in figures 1.1 through 1.7 is for the purpose of illustrating portions of the vacuum cleaner body that forms no part of the claimed design.
